UNITED STATES PATENT OFFICE.

LEWIS A. FRYE, OF LOS ANGELES, CALIFORNIA.

TOWER FOR SUSPENDED RAILWAYS.

Application filed March 5, 1924. Serial No. 697,015.

To all whom it may concern:

Be it known that I, LEWIS A. FRYE, a citizen of the United States, residing at Los Angeles, in the county of Los Angeles and State of California, have invented new and useful Improvements in Towers for Suspended Railways, of which the following is a detailed specification.

This invention relates to towers for suspended railways and while the structure embodying my invention may be advantageously used in many and various situations, it is especially well suited to the purpose of supporting girders or rails used in connection with suspended or elevated railways. In order to more definitely describe the invention, I have chosen to illustrate it in connection with a particular type of railway, namely, a suspended mono-railway, but this is not to be construed as a limitation on the invention.

In the usual suspended mono-rail system, the load is normally carried beneath and in vertical alinement with the traction rail, a goose-neck hanger usually serving to connect the load with a truck or trucks riding on the rail. Therefore, in order to provide the necessary clearance for the load and goose-neck, the traction rail and its underlying girders must be supported from one side only. To comply with this requirement, a supporting tower must have its column set out of vertical alinement with the rail girders, while cantilever beams extend from the column to provide the necessary girder support.

It is among the objects of my invention to provide a tower of the general nature described above, which will be of minimum weight, occupy a minimum of space and yet have the requisite rigidity and strength. I have devised novel means for fixing the cantilever beam against vertical rotation about its point of support on the column, this means generally consisting of a tension member secured to an extension of the cantilever and extending downwardly and inwardly towards the base of the column, at which point it is anchored in a footing. The tension member also serves the additional and important purpose of bracing the column against flexure caused by the off-center imposition of load. The elements of my tower structure may be readily fab-

ricated from standard material and may be quickly and easily erected in the field.

I have also combined certain of the structural elements to serve several purposes and have evolved a novel system of bracing the column and distributing the strain through the tower, as will be disclosed in the following detailed description.

The tower illustrated is particularly adapted, although not limited, for use in connection with country or "high-line" railway systems where traffic is comparatively light and where the strains incident to frequent starting and stopping of trains are reduced to a minimum, and I therefore prefer to use a wooden tower column having a desirable degree of strength and flexibility and usually easily procurable in the field. In this connection, I have devised certain novel joints for uniting the metal and wooden elements of the tower to secure a proper bond between them.

Other objects and features of novelty will be set out in the following description, reference being had to the accompanying drawings, in which:

Fig. 1 is a side elevation of a tower showing a loading platform in connection therewith, and also showing a mono-rail car supported on an associated U-rail.

Fig. 2 is a fragmentary section taken on line 2—2 of Fig. 1, showing one method of supporting a loading platform from certain elements of the tower, proper.

Fig. 3 is an enlarged section on line 3—3 of Fig. 1.

Fig. 4 is an enlarged vertical section on line 4—4 of Fig. 1.

Fig. 5 is a top plan view of a column cap which is shown in section in Fig. 4.

Fig. 6 is a fragmentary elevation of the column footing and shoe, as viewed from the portion of arrow 6 in Fig. 1.

Fig. 7 is a horizontal section on line 7—7 of Fig. 6.

Fig. 8 is a vertical section on line 8—8 of Fig. 6.

Fig. 9 is a fragmentary view showing details of the connection between the tower column and cantilever, parts being shown in broken away section.

In the following specification I first generally describe the main elements of the tower and point out their function and co-

action, leaving the details of structural form and connecting elements to be treated later.

Column 10, preferably of wood, having a shoe generally indicated at 11, rests on footing 12 of masonry or concrete. Anchor bolts 13 are imbedded in the footing and extend upwardly through the shoe, nuts 14 serving to hold the shoe and hence the column in position on the footing.

10 A metal cap 15, channeled at 16 on its upwardly disposed face, is carried on the top of column 10 and serves as a bearing plate for the cantilever beam 17 which is preferably an I-beam provided with stiffening braces or angles 18 between its flanges. Straps 19 are bolted to column 10 at 20 and thus extend upwardly and inwardly to meet opposite sides of beam web 21 to which they are riveted at 22 (see Figs. 3 and 4), thus serving to hold the beams to the column and as braces for the beam. Angles 23 form a connection between the end of beam 17 and girder 24 which supports the U or traction rail 25. A car 26 is suspended by hanger 27 from truck 28, this showing of truck and car being made merely to illustrate the disposition of load on the column and not as a part of the invention. It will be understood that rail 25 may be used for supporting loads other than cars. For instance, it may be used in connection with suspended, traveling cranes, etc.

35 Cantilever 17 has a portion 17^a extending from the column on the side opposite to that carrying girder 24, and a T-iron tension member 29 is secured to the end of extension 17^a at 30 and thence inclines downwardly and inwardly towards the base 40 of the tower, being secured by splice plates 31 to post 32 which extends downwardly through footing 12 and is clamped at 33 to the transversely arranged rail or anchor 34, commonly known as a "dead-man", and 45 which is embedded in a lateral extension of footing 12. It will be noted that the point at which member or element 29 is anchored, lies within footing 12 and is approximately in vertical alinement with the longitudinal axis of column 10. Therefore, in later discussion, element 29 may be considered as being anchored at the base of the column.

50 A strut 35, preferably made up of I-beams 36, cover plates 37 and extension plates 38 and 39, is secured at one end to column 10 by angles 40 and is bolted at 41 to tension members 29.

60 Corner or knee braces 42 serve to reinforce the structure against relative movement between column 10 and beam 17, and these braces are preferably made up and secured as follows: Gusset plates 43 have outlining angle iron reinforcements 44, 45 and 46, each riveted to its respective gusset plate. The horizontal leg of each angle

iron 45 is riveted to the lower flange of beam 17 at 47, while the vertical angle irons 44 are secured to the column by lag screws 48 (see Fig. 9).

70 An angle iron brace 49 is secured to the tower at approximately the point of junction between beam 17 and column 10, preferably by bolts 50 through inner knee brace 42, and hence extends downwardly and outwardly, being secured at its lower end to inclined post 51 by splice plates 52. Post 51, in turn is clamped at 53 to anchor 34. Brace 49 preferably crosses member 29 at strut 35 and is secured to member 29 and strut by bolts 41.

75 Extending laterally from and secured to column 10 by angles 54, is beam 55, while secured to struts 35 by angles 56 is beam 57, these two beams serving as a support for platform 58 which is thus maintained at a height to enable car 26 to be loaded or unloaded therefrom. Stairways 59 and 60 lead from the ground to platform 58 and are supported by posts 61 and platform 58.

80 Now, the imposition of load 26 on the free end of cantilever 17, exerts a compressive force on column 10 and, by reason of the off-center position of the load with respect to the longitudinal axis of the column, also tends to rotate the beam in a counterclockwise direction, as viewed in Fig. 1, giving the column a tendency towards lateral flexure, compressing the fibers at the left of the neutral axis, and placing the fibers at the right of the neutral axis under tension. 100 Member 29, however, is placed under tension and has the effect of counterbalancing the load on the cantilever to transform the stress on the column into direct vertical thrust, which the column is best able to withstand. 105 At the same time, considering beam extension 17^a as a strut, member 29 has the effect of a truss rod, bracing the beam against flexure.

110 Brace 49 acts as a wind brace and counteracts the tendency of the column and tower proper to rotate vertically about the column base when a load is placed on the end of the cantilever. Furthermore, that portion of brace 49 which extends from knee brace 42 to strut 35, combines with the strut and that portion of member 29 which extends from strut 35 to the base of the column to form a vertical truss for the column and thus stiffen it against a flexure.

115 In Figs. 6, 7 and 8 I have illustrated a preferred form of column shoe and will now describe it in detail. To bed plate 62 are riveted the opposed angle irons 63, with their vertical legs 64 spaced apart to receive the base of column 10 between them, the end of the column resting on the bed plate. 120 To complete the column socket, vertical side plates 65 are held to the bed plate by angles 66 riveted to bed and side plates. Bolts 67

through the side plates and column, and bolts 68 through angle legs 64, unite the column and shoe.

Angle irons 69 are riveted at 70 to side plates 65 and the horizontal legs 71 of these angles form lateral flanges extending along the side plates and vertically spaced above the bed plate. Vertically arranged channels 72 extend between the bed plate and flanges 71 and are riveted to side plates 65 at 73. Anchor bolts 18 extend upwardly from footing 12 and through suitable vertically alined apertures in bed plates and flanges, nuts 14 being threaded on the anchor bolts and into engagement with the tops of flanges 71 to hold the shoe and column to the footing. Channels 72 serve as stiffening spacers between bed plate 62 and flanges 71, and, preferably, the channels are so located that the anchor bolts extend upwardly between the channel flanges. In this way, structural reinforcement between the bed plate and shoe flanges is accomplished at the point of greater stress, namely, where compressive effort is exerted by threading nuts 14 on the plate flanges to draw the shoe firmly down to the footing.

While I have shown and described a preferred embodiment of my invention, various changes in structure and design may be made without departing from the spirit of my invention, and therefore I do not wish to be limited to the structural details shown and described except for such limitations as a fair interpretation of the claims may import.

Having described a preferred form of my invention I claim:

1. A tower structure for suspended rail-ways, embodying a vertical column anchored at its base, a cantilever supported by the top of the column and extending oppositely beyond its point of support on the column, a tension member secured to the cantilever extension and extending downwardly and inwardly towards the base of the column, and means for anchoring the tension member.

2. A tower structure for suspended rail-ways, embodying a vertical column anchored at its base, a cantilever supported by the top of the column and extending oppositely beyond its point of support on the column, a tension member secured to the cantilever extension and extending downwardly and inwardly towards the base of the column, and means for anchoring the tension member at a point substantially in alignment with the longitudinal axis of the column.

3. A tower structure for suspended rail-ways, embodying a footing, a vertical column anchored to the footing, a cantilever supported by the top of the column and extending oppositely beyond its point of support on the column, a tension member se-

cured to the cantilever extension at a point laterally spaced from the column and extending downwardly and inwardly towards the column base, and means for anchoring the tension member in the footing.

4. A tower structure for suspended rail-ways, embodying a vertical column anchored at its base, a cantilever supported by the top of the column and extending oppositely beyond its point of support on the column, a tension member secured to the cantilever extension at a point laterally spaced from the column and thence extending downwardly and inwardly towards the column base, means for anchoring the tension member at the base of the column and a horizontal strut carried by the column between its base and the cantilever, said strut extending towards and being secured to the tension member.

5. A tower structure for suspended rail-ways, embodying a vertical column anchored at its base, a cantilever supported by the top of the column and extending oppositely beyond its point of support on the column, a tension member secured to the cantilever extension at a point laterally spaced from the column and thence extending downwardly and inwardly towards the column base, means for anchoring the tension member at the base of the column, a brace joined to the structure near the junction of the column and beam and thence extending downwardly and outwardly with respect to the base of the column, and means for anchoring the brace at its lower extremity.

6. A tower structure for suspended rail-ways, embodying a vertical column anchored at its base, a cantilever supported by the top of the column and extending oppositely beyond its point of support on the column, a tension member secured to the cantilever extension at a point laterally spaced from the column and thence extending downwardly and inwardly towards the column base, means for anchoring the tension member at the base of the column, a brace joined to the structure near the junction of the column and beam and thence extending downwardly and outwardly with respect to the base of the column, and means for anchoring the brace at its lower extremity, the tension member and brace crossing each other and being secured together at their point of crossing.

7. A tower structure for suspended rail-ways, embodying a vertical column anchored at its base, a cantilever supported by the top of the column and extending oppositely beyond its point of support on the column, a tension member secured to the cantilever extension at a point laterally spaced from the column and thence extending downwardly and inwardly towards the column base,

means for anchoring the tension member at the base of the column, a brace joined to the structure near the junction of the column and beam and thence extending downwardly and outwardly with respect to the base of the column, means for anchoring the brace at its lower extremity, the tension member and brace crossing each other and being secured together at their point of crossing, a horizontal strut secured to the column and extending to the crossing point of the tension member and brace, and means for uniting the strut, tension member and brace at said point of crossing.

15. 8. A tower structure for suspended rail-ways, embodying a vertical column anchored at its base, a cantilever supported by the top of the column and extending oppositely beyond its point of support on the column, a tension member secured to the cantilever extension at a point laterally spaced from the column and thence extending downwardly and inwardly towards the column base, a brace joined to the structure near the junction of the column and beam and thence extending downwardly and outwardly with respect to the base of the column, the tension member and brace crossing each other and being secured together at their point of crossing, an anchor, and means for attaching the lower extremities of the tension member and brace to the anchor at laterally spaced points.

9. A tower structure for suspended rail-ways, embodying a vertical column anchored at its base, a cantilever supported by the top of the column and extending oppositely beyond its point of support on the column, a tension member secured to the cantilever ex-tension at a point laterally spaced from the column and thence extending downwardly and inwardly towards the column base,

means for anchoring the tension member at the base of the column, a horizontal strut carried by the column between its base and the cantilever, said strut extending towards and being secured to the tension member, and platform supporting members carried by the beam and strut.

10. In a structure of the character de-scribed, means for uniting a column and a horizontal I beam on top thereof, said means comprising plates secured to the sides of the column and extending upwardly and in-wardly from the top of the column to meet the opposite sides of the I beam web, and means for securing the plates to the web at their points of meeting.

11. In a structure of the character de-scribed, means for uniting a column and a horizontal I beam on top thereof, said means comprising plates secured to the sides of the column and extending upwardly and in-wardly from the top of the column to meet the opposite sides of the I beam web, means for securing the plates to the web at their points of meeting, and knee braces in the meeting angles between the column and beam.

12. In a structure of the character de-scribed, a footing of concrete, a column shoe including a bed plate adapted to rest on the footing, lateral flanges on the shoe spaced above the bed plate, vertically channeled spacers between the plate and flanges, and anchor bolts embedded in the concrete and extending upwardly through the bed plate, thence extending vertically through the channels in the spacers and then through the lateral flanges.

In witness that I claim the foregoing I have hererunto subscribed my name this 22nd day of December, 1923.

LEWIS A. FRYE.
